The ornamental design **CLAIM** container, as shown and described.

DESCRIPTION

FIG. 1 is a perspective view of a container showing our new design;

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of threads, part of the top portion and part of the bottom portion of the container is for illustrative purposes only and forms no part of the claimed design.

The stippling shown in the drawing disclosure denotes a gradation of color.
